UNITED STATES PATENT OFFICE.

LOUIS A. BRENEMAN, OF ST. PAUL, MINNESOTA, ASSIGNOR TO MINNESOTA MANUFACTURERS' ASSOCIATION, OF NORTH ST. PAUL, MINNESOTA, A CORPORATION OF MINNESOTA.

ELEVATOR.

1,240,172.

Specification of Letters Patent. Patented Sept. 18, 1917.

Application filed June 3, 1916. Serial No. 101,495.

To all whom it may concern:

Be it known that I, Louis A. BRENEMAN, a citizen of the United States, residing at St. Paul, in the county of Ramsey and 5 State of Minnesota, have invented new and useful Improvements in Elevators, of which the following is a specification.

My invention relates to improvements in elevators.

10 Elevators of the type having endless traveling chains with trays thereon adapted to automatically receive loads at various stations in their upward travel and discharge the same at various stations 15 in their downward travel are widely used in mercantile establishments and other places. These trays are carried by hangers pivotally attached to the drive chain, and are provided with a frame, designed 20 to prevent the tilting of said hangers in their upward and downward travel at the sides of the elevator. In crossing over from one side to the other at the top of the elevator, said hangers have a tendency to tip if the loads upon the trays are 25 unbalanced, and my present invention has for its principal object to provide, in an elevator of the class referred to, simple and efficient means to prevent the tilting of 30 the tray hangers at the upper turn of the elevator.

Other objects are secured by various novel features of construction and combinations of parts which will be hereinafter described 35 and pointed out in my claims.

In the drawings, Figure 1 is a front view of my improved elevator, showing but one of several tray hangers; Fig. 2 is a side view thereof; Fig. 3 is a diagrammatical 40 view of the essential parts of my invention; Fig. 4 is a sectional view taken on the line 4-4 of Fig. 3; and Fig. 5 is a detail sectional view of a tray hanger, showing its connection with a drive chain.

45 Referring to the accompanying drawings, I have used the numeral 10, with various suffixes, to indicate the different parts of the elevator frame, which consists of inner and outer sets of channeled members oppositely arranged to provide ways for parts hereinafter described. The outer beams 10^a form an elongated inverted U-shaped structure, the top 10^b being semicircular in form. Inner bars 10^c are secured by straps 11 upon 50 the beams 10^a in spaced parallel relation

therewith (Fig. 1), and a curved bar 10^d is similarly secured to the curved beam 10^b. A driving sprocket wheel 12 near the upper end of the frame is mounted upon a shaft 13 which is journaled in a bearing 14 on 60 a cross-piece 15, and said wheel turns within the frame and passes through slots 16 in the ends of the bars 10^c (Fig. 2). An idler sprocket wheel 17 near the bottom of the frame is furnished with a stub shaft 18 65 which is journaled in a bearing 19 on a cross-piece 20. The drive chain 21 passes around said sprocket wheels 12 and 17 and the portions of the chain between said wheels pass through ways between the beams 10^a 70 and bars 10^c. The drive shaft 13 upon which the sprocket wheel 12 is mounted is driven through suitable gearing from a power pulley 22 or by other suitable means. Tray hangers 23 carrying trays 24 are secured at intervals to the drive chain 21. 75 These hangers are identical and a description of one will suffice for all. A hanger comprises a hanger bar 25 having at its rear side an integral guide block 26, a boss 80 27 and ears 28 arranged respectively at the upper end, middle and lower end of said hanger bar. A gear segment 29 is cast integral with or otherwise secured to the lower end of said hanger bar which end 85 is flattened out to form a plate 30 (Fig. 1) overlapping said gear segment and providing a segmental shoulder 31 (Fig. 4) around said gear. A pin 32, secured in the hanger bar 25 and passing through the 90 guide block 26, is provided with a reduced end 32^a which serves as a link pin for certain links in the chain 21 and furnishes a connection between said hanger bar and chain. The block 26 travels along the ways 95 between the channeled members of the frame, the curved face 33 (Fig. 5) bearing against the front flanges thereof and the curved edges 34 (Fig. 1) bearing against the webs of said channeled members. A 100 guide wheel 35 journaled on a pintle 35^a in the boss 27 also travels in the ways and holds said hanger bar against tipping movements. Between the ends of the guide bars 10^c and 10^d, the ways in which the guide 105 wheels 35 and guide blocks 26 travel are interrupted to permit the passage of the latter over the driving sprocket 12. During such travel of the guide block 26, the guide wheel 35 passes through the curved way at 110

the top of the elevator. To supplement the guide wheel 35 and to hold the hanger bar 25 in upright position throughout the upper turn of the elevator, I arrange a spur gear 36 below the driving sprocket 12 which meshes with the gear segment 29 on the hanger bar as it passes over said sprocket. Said spur gear 36 is mounted on a shaft 37 journaled in bearings 38 and said shaft 10 is supplied with a sprocket wheel 39 driven by a chain 40 from a sprocket wheel 41 on the drive shaft 13. The arc of the curved way has a radius equal to that of the sprocket wheel 12 and the spur gear 36 is 15 turned at such speed with respect to the travel of the chain 21 that the hanger bar 25 remains in vertical position.

At the turn at the bottom of the elevator, no such provision need be made to insure the 20 upright position of the hanger bars for the reason that the trays in this situation are always empty and the hanger bars 25 are retained in upright position by gravity.

Guard strips 42 are fixed upon the frame, 25 as illustrated in Fig. 1, in positions adjacent to the path of the gear segments 29. These strips bear against said gear segments and straighten the hanger bars if they are out of plumb and insure the registration of the 30 guide wheels 35 with the openings of the different ways.

A load upon a tray being offset from the connection between the hanger bar 25 and chain 21 would cause considerable stress 35 upon the connecting pin 32^a, if the lower end of the hanger bar were not supported or braced. I provide such a support in a roller 43 (Fig. 4) which is revoluble between the ears 28 and which rolls upon the frame 40 members through that part of the path of said hanger where loads are carried, except in crossing from one side of the elevator to the other, and while in this situation the segmental shoulder 31 bears against the side of 45 the spur gear 36 and braces the hanger bar.

Having described my invention, what I claim as new and desire to protect by Letters Patent, is:

1. In an elevator, a frame, a pair of 50 sprocket wheels revoluble on said frame and arranged one above the other, a chain passing over said sprocket wheels, means to drive the chain, a hanger pivotally attached to said chain, a tray on the lower end of the

hanger, a gear segment on the hanger, a 55 driven spur gear below the upper sprocket wheel arranged to mesh with said gear segment and hold the hanger in upright position at the upper turn, and a segmental shoulder on the hanger adapted to slidably 60 bear against the side of said spur gear at said upper turn, to support the hanger.

2. In an elevator, a frame having vertical ways at its sides and an arched way at the top thereof, a pair of sprocket wheels revoluble on said frame and arranged one above the other, a chain passing over said sprocket wheels, means to drive the chain, a hanger 65 pivotally attached to said chain, a tray on the lower end of the hanger, a guide wheel 70 on the hanger, above the point of connection with the chain, arranged to travel in said ways, a gear segment on the hanger beneath said point of connection, a driven spur gear below the upper sprocket wheel, said gear 75 segment and guide wheel being adapted to cooperate respectively with said spur gear and arched way to hold the hanger in upright position at the upper turn of the elevator, and a segmental shoulder at the outer 80 edge of said gear segment designed to slidably bear against the rim of said spur gear and brace the hanger at said upper turn.

3. In an elevator, a frame having vertical ways at its sides and an arched way at the 85 top thereof, a pair of sprocket wheels revoluble on said frame and arranged one above the other, a chain passing over said sprocket wheels, means to drive the chain, a hanger having an integral guide block thereon 90 adapted to travel in said vertical ways, a pivot passing centrally through said guide block and connected with said chain, a tray on the lower end of the hanger, a guide wheel on the hanger, above the point of connection with the chain, arranged to travel in said ways, a gear segment on the hanger beneath said point of connection, and a driven spur gear below the upper sprocket wheel, said gear segment and guide wheel 95 being adapted to cooperate respectively with said spur gear and arched way to hold the hanger in upright position at the upper turn.

Whereof, I have hereunto subscribed my 100 name to this specification.

LOUIS A. BRENEMAN.
